JACK

John W. Bour, Los Angeles, Calif.

Application August 13, 1946, Serial No. 690,226

19 Claims. (Cl. 254—1)

1

This invention has to do with a jack and is more specifically concerned with a combined jack and operating means therefor, it being a general object of the invention to provide a simple, effective, convenient jack and operator that can be used to advantage in jacking up automobiles or the like.

Automobiles, in fact motor vehicles generally, equipped with pneumatic tires, require lifting or parts or portions when a tire becomes deflated and it is common to employ a simple mechanical or hydraulic jack for this purpose. It is simple, in practice, to provide a jack mechanism, as such, that will effectively handle the load involved and will operate through the desired distance. However, it is generally very difficult and inconvenient to operate the jacks that are provided for this purpose since they are, generally, located well under the vehicle in order to be most effective, and when so located they are most inaccessible.

The broader principles of my invention are applicable, generally, to jacks of various types. However, since hydraulic jacks are most advantageous in many situations and since this type of jack lends itself to the present invention, I will in this disclosure make reference to the invention as carried out with a hydraulic jack, it being understood that such reference is not to be construed as a limitation upon the broader aspects of the invention.

A general object of my invention is to provide a simple jack mechanism for the general class of use referred to which mechanism is of simple, practical, inexpensive construction and which is effective and dependable in action.

A further object of my present invention is to provide a jack operator which can be conveniently handled and manipulated to apply or locate, to manipulate or operate, and to withdraw a jack from beneath an object such as a motor vehicle or the like.

It is another object of my invention to provide a mechanism combining a jack and an operator therefor whereby the jack portion proper can be conveniently handled through the operator or operating mechanism for insertion to and removal from position under a vehicle or the like, and which operator is such that it can be manipulated easily and in a most advantageous manner to work the jack both to elevate it and to release it in a simple, convenient manner and without danger of displacing the jack from the desired position.

The various objects and features of my inven-

2

tion will be fully understood from the following detailed description of a typical preferred form and application of my invention, throughout which description reference is made to the accompanying drawings, in which:

Fig. 1 is a side elevation of the jack and operator that I have provided. Fig. 2 is a plan view of the parts shown in Fig. 1. Fig. 3 is an enlarged detailed sectional view taken substantially as indicated by line 3—3 on Fig. 2. Fig. 4 is an enlarged detailed sectional view taken substantially as indicated by line 4—4 on Fig. 2. Fig. 5 is a transverse sectional view taken as indicated by line 5—5 on Fig. 3. Fig. 6 is a sectional view taken as indicated by line 6—6 on Fig. 3 and Fig. 7 is a view of one of the parts removed from the rest of the structure.

The jack proper A, which I have shown in the drawings, is of the hydraulic type and is adapted to be handled, that is, both manipulated and operated, by the operator B that I have provided. The jack A is preferably either a single or two-stage hydraulic jack involving, generally, a base 10 having an upstanding boss 11 carrying a cylinder 12. A piston 13 operates in the cylinder and a piston or lift rod 14 connects to the piston 13 and extends upwardly through a head 15 at the upper end of the cylinder. A work engaging plate 16 is provided on the upper end of the rod 14 above the head 15, the plate being designed and proportioned to effectively fit or engage the particular object to be lifted.

The pump involves a reservoir R carrying a supply of fluid, which reservoir may be formed by a jacket 17 surrounding the cylinder 12 and extending between the boss 11 and the head 15, as shown throughout the drawings. The jack further involves a pump 18 for handling operating fluid so that it receives such fluid from the reservoir R and delivers it under pressure into the lower end of the cylinder 12 below the piston 13. The particular pump 18 illustrated in the drawings is a cylinder and piston type of pump carried by the base of the jack to extend in a substantially horizontal direction although I prefer to locate it so that it extends from one side of the boss 11 and slightly upward to be slightly inclined as shown in Fig. 3 of the drawings. The particular pump illustrated involves, generally, a cylinder 20 attached to the boss 11 of the base at a socket 21 provided in the boss, and I have shown the cylinder screw threaded into the socket 21. A piston 22 is slidably carried in the cylinder 20 and a piston rod 23 connects to the piston 22 and projects from the cylinder 20 through a cap

24 at the outer end of the cylinder. I provide a head 25 at the outer end of the rod 23 which head has an opening 26 for the reception of a part of the operator, as will be hereinafter described. In practice I may employ any suitable means to maintain the head 25 in a fixed rotation position. It is desirable that the head 25 be maintained in a fixed rotative position and for this purpose I prefer to provide a rod 23 with a flat side 27 and form the opening 26 in the cap 24 so that it fits the contour or cross sectional configuration of the rod and thus keys or holds the rod against rotation. A spring 29 is preferably provided in the cylinder 20 between the cap 24 and the piston 22 to normally yieldingly urge the piston 22 toward the inner end of the cylinder.

The pump or pump means 18 involves suitable valve means for controlling the flow of fluid. In the preferred construction two recesses or chambers 30 and 31 are provided in the bottom of the socket 21 and spring pressed ball valves 32 and 33 are carried by and operate in the chambers 30 and 31, respectively. The valve 32 is an inlet valve while the valve 33 is an outlet valve. An inlet port 35 connects the reservoir R with the chamber 30 and the valve 32 seats in the bottom of the chamber under the influence of a suitable spring. A delivery port 36 connects the chamber 31 with the cylinder 12 below the piston 13 and the valve 33 cooperates with a seat plate 38 confined in the bottom of the socket 21 by the end of the cylinder 20 that screw threads into the socket. The seat plate 38 has a seat 39 with which the valve 33 cooperates and it has a port 40 that registers with the chamber 30. A pin 42 serves to orient the plate 38 and to hold it against rotation from the desired operating position.

The jack further provides a release means or release valve device 43 by or through which fluid under pressure beneath the piston 13 can be released to flow into the reservoir R. The means 43 as illustrated in the drawings involves a by-pass port 44 formed in the boss between the lower end of the cylinder 12 and the lower end of reservoir R, which port is formed by suitable bored openings in the manner shown in Fig. 4. A slide valve is provided in connection with the by-pass port to control flow therethrough, the valve being adapted to be opened by positive operating means to allow free flow between the reservoir and cylinder. The particular valve construction illustrated involves a fitting 45 carried by or threaded into the boss 11 to have a seat portion 46 at a chamber 47 in the port 44 which chamber carries a valve 48 normally held against the seat by a spring 49. The parts are arranged and related so that pressure of fluid in the cylinder 12 is closed off from the reservoir. An operating stem 50 is carried by the fitting 45 and is engaged by the spring 49 carried in the chamber 47 so that the stem is normally yieldingly held in an up position where the valve 48 is allowed to close the port 44. The stem 50 projects above the fitting or to a position where it is exposed and can be engaged for operation. In the arrangement illustrated the stem 50 projects so that it is exposed and can be depressed and when depressed it engages the valve 48 and moves it down against the spring 49 opening the by-pass 44.

The operation of the jack as hereinabove described will be apparent, that is, it will be readily understood how reciprocation of the pump rod 23 will cause the pump to draw fluid from the reservoir R and deliver it under pressure to the lower end of the cylinder 12 so that it acts to force the

piston 13 up in the cylinder 12 and thus elevate the plate 16 on the upper end of the rod 14. When it is desired to release the jack so that the piston 13 returns to the lower end of the cylinder 12 the stem 50 is depressed opening valve 48 so that the by-pass 44 is opened thus providing free communication between the cylinder and the reservoir.

The operator that I have provided is preferably 10 a light, simple device or tool provided with means for engaging the jack A so that the jack can be slid or manipulated to the desired position and can be held in that position, provided with means for operating the mechanism 18 of the jack and 15 provided with means for operating the release means 43 of the jack. The operator in the form illustrated involves, generally, an elongate body 55 carrying means 56 for connection with the jack A, operating means 51 for the pump of the 20 jack and operating means 58 for the release means of the jack.

The body 55 of the operator is preferably a light, rigid elongate member or shaft provided at what I will term its inner end with a handle or 25 hand grip 60 and serving as a mounting for the means 56, 57 and 58. In the preferred construction the body 55 may be formed of sheet metal and may be made U-shaped in cross sectional configuration so that it is light, strong and rigid.

The means 56 provided at the outer or forward 30 end of the body 55 serves to connect the body with the jack A. In the particular construction illustrated I show a jack wherein the boss 11 has an upwardly facing socket 61 adjacent the pump 18. 35 When the jack is thus formed the means 56 may involve an angularly disposed part or finger 62 on the forward end of the body 55, which finger is made to properly cooperate with the socket. In the preferred construction the socket 61 is rectangular or polygonal in plan configuration and the finger 62 is correspondingly shaped and made to fit or key into the socket. As shown in Fig. 3 of the drawings I provide an opening in one 40 wall of the socket 61, preferably the outside wall or the wall which faces the operator, and I provide a hook portion 51 on the means 56 which engages in the opening. It will be apparent that the body is connected with the jack to enable the person using the equipment to not only push or pull the jack along a horizontal support such 45 as the ground, but also to lift it, and to turn it to any desired angle by swinging the body 55 from side to side. In the case illustrated I have shown the outer end portion of the body 55 and the finger 62 of means 56 reinforced by a core 63 within the sheet metal that forms the body and the finger.

The means 57 carried by the body 55 for operating the pump 18 of the jack preferably includes a pump rod 64 that extends longitudinally 50 of the body 55 and which is provided at the outer end portion of the body with a laterally projecting part or tongue 65 for engagement in the opening 26 in the head 25 of piston rod 23. The means 57 further provides means for operating or reciprocating the rod 64 and this means 55 preferably includes a simple lever 66 pivotally connected to the body 55 at 67. The inner end of the pump rod 64 is pivotally connected to the lever 66 at 68 and at a point suitably removed 60 from the point 67. The lever 66 has a projecting end outward of or beyond the pivotal connection 68 which part forms a handle that can be conveniently gripped so that the lever can be 70 oscillated in order to reciprocate the rod 64.

The means 58 provided for operating the release means 43 of the jack preferably involves a shaft 70 carried by the body 55 to extend longitudinally thereof, which rod has a laterally projecting foot 71 at the inner end portion of the body 55, which foot is adapted to cooperate with the stem 50 of the release means 43. The shaft 70 extends to the handle portion 60 of the body 55 and at the end of the handle it is provided with an operating knob 72 so that the shaft can be conveniently rotated. The foot 71 on the shaft 70 overlies the upper end of the stem 50 as shown in Fig. 5 and when the shaft is rotated in the proper direction the foot is swung or moved down as indicated by the arrow X in Fig. 5, causing the stem 50 to be depressed with consequent opening of the valve 48 as above described.

In the general arrangement of parts provided in the operator that I have described the pump rod 64 and the shaft 70 extend substantially parallel with the body 55 and when the parts are not in use the lever 66 is folded down to be substantially parallel with the body, with result that the assembly forms a neat, compact unit. It is preferred in practice to guide the pump rod to the outer end portion of the body, as by a suitable guide bracket 80, and also to guide the shaft 70 at the outer end portion of the body 55, as by a guide bracket 81.

In using the equipment that I have provided the finger 62 on the outer end of the body 55 is engaged in the socket 61 simultaneously with engagement of the tongue 65 in the opening 26 of head 25. This establishes connection or engagement between the operator and the jack and locates the foot 71 of means 58 in position over the stem 50 of means 43. With the parts thus engaged a person handling the operator from the handle portion 60 can slide the jack under a car or like object to locate it in the desired position, and if necessary can turn the jack to the desired rotative position. When the jack is located the handle 65 is oscillated causing the pump rod 64 to be reciprocated. Reciprocation of the rod 64 reciprocates the rod 23 of pump 18 causing fluid to be pumped from the reservoir into the cylinder of the jack. This operation can be continued and as it is being performed the operator can hold the handle 60 with one hand while he operates the lever 66 with the other hand. When it is desired to release the jack it is merely necessary for the user to turn the knob 72 in a manner to move the foot 71 into engagement with the stem 50 and depress the stem opening the valve 48. By suitable manipulation of the knob 72 the jack can be released or lowered at the desired speed.

When the jack has been lowered it can be withdrawn from beneath the vehicle or from the location of use, and when not in use the operator B can be disengaged from the jack A by simply lifting the finger 62 and tongue 65 from the socket 61 and opening 26, respectively.

From the foregoing description it will be apparent that I have, by my present invention, provided an extremely simple, inexpensive compact and yet effective apparatus. The jack A is simple and compact in form and the operator B is simple, inexpensive and light. The entire mechanism is easy to handle and operate and when not in use can be stored in a very limited space.

Having described only a typical preferred form and application of my invention, I do not wish to be limited or restricted to the specific details herein set forth, but wish to reserve to myself any variations or modifications that may appear

to those skilled in the art and fall within the scope of the following claims.

Having described my invention, I claim:

1. A unitary jack operable by an operator having an elongate body with a coupling element at one end and carrying two operating elements including, a base having an open socket releasably receiving the coupling element of the operator, an actuating pump with a working part engageable by one of the operating elements of the operator when the coupling element is engaged in the socket, and a release means controlling the pump engageable by the other operating element of the actuator.
2. A unitary jack operable by an operator having an elongate body with a coupling element at one end and carrying two operating elements including, a base having an open socket releasably receiving the coupling element of the operator to releasably connect the jack and actuator, an actuating pump with inlet and outlet valves and a working part engageable by one of the operating elements of the operator when the actuator and jack are connected, and a release valve operable to release pressure established by the pump and engageable by the other operating element of the actuator when the actuator and jack are connected.
3. An actuator for a jack having an operating part to be reciprocated, and a release means with an operator to be depressed for releasing the jack including, an elongate body, a rod carried by the body and having means for connection with the operating part, means for reciprocating the rod, a shaft rotatably carried by the body and carrying an element engageable with the operator when the rod is connected with the operating part.
4. An actuator for a jack having an operating part to be reciprocated, and a release means with an operator to be depressed for releasing the jack including, an elongate body with a projecting finger connectable with the jack, a rod carried by the body and having means for connection with the operating part, means for reciprocating the rod, a shaft rotatably carried by the body and carrying an element engageable with the operator when the rod is connected with the operating part.
5. An actuator for a jack having an operating part to be reciprocated, and a release means with an operator to be depressed for releasing the jack including, an elongate body with a projecting finger connectable with the jack, a rod carried by the body and having a projecting tongue for connection with the operating part, means for reciprocating the rod, a shaft rotatably carried by the body and carrying an element engageable with the operator when the rod is connected with the operating part.
6. An actuator for a jack having an operating part to be reciprocated, and a release means with an operator to be depressed for releasing the jack including, an elongate body, a rod carried by the body and having means for connection with the operating part, means for reciprocating the rod, a shaft rotatably carried by the body and carrying a laterally projecting foot engageable with the operator when the rod is connected with the operating part.
7. An actuator for a jack having a socket, an operating pump with a reciprocating piston rod, and a release valve with an exposed operating stem including, an elongate body having a handle at its inner end, a finger at the outer end of the body engageable in the socket to connect the

body and jack, an operating rod carried by the body and having a projecting tongue to connect with the piston rod, and a shaft carried by the body having a projecting foot for operating the stem.

8. An actuator for a jack having a socket, an operating pump with a reciprocating piston rod, and a release valve with an exposed operating stem including, an elongate body having a handle at its inner end, a finger at the outer end of the body engageable in the socket to connect the body and jack, an operating rod carried by the body and having a projecting tongue to connect with the piston rod, and a shaft carried by the body having a projecting foot for operating the stem, the body, operating rod and shaft being substantially parallel with each other.

9. An actuator for a jack having a socket, an operating pump with a reciprocating piston rod, and a release valve with an exposed operating stem including, an elongate body having a handle at its inner end, a laterally projecting finger at the outer end of the body engageable in the socket to connect the body and jack, an operating rod carried by the body and having a laterally projecting tongue to connect with the piston rod, and a shaft carried by the body having a laterally projecting foot for operating the stem.

10. An actuator for a jack having a socket, an operating pump with a reciprocating piston rod, and a release valve with an exposed operating stem including, an elongate body having a handle at its inner end, a finger at the outer end of the body engageable in the socket to connect the body and jack, an operating rod carried by the body and having a projecting tongue to connect with the piston rod, operating means for the operating rod carried by the body and operable to reciprocate said operating rod, and a shaft carried by the body having a projecting foot for operating the stem.

11. An actuator for a jack having a socket, an operating pump with a reciprocating piston rod, and a release valve with an exposed operating stem including, an elongate body having a handle at its inner end, a finger at the outer end of the body engageable in the socket to connect the body and jack, an operating rod carried by the body and having a projecting tongue to connect with the piston rod, an operating lever pivotally connected with the body and with the operating rod, and a shaft carried by the body having a projecting foot for operating the stem.

12. In combination a jack having a socket, an operating pump with a reciprocating piston rod, and a release valve with an exposed operating stem, and an operator including an elongate body having a handle at its inner end, a finger at the outer end of the body engageable in the socket to connect the body and jack, an operating rod carried by the body and having a projecting tongue to connect with the piston rod, and a shaft carried by the body having a projecting foot for operating the stem.

13. In combination, a jack having a socket, an operating pump with a reciprocating piston rod, and a release valve with an exposed operating stem, and an operator including an elongate body having a handle at its inner end, a finger at the outer end of the body engageable in the socket to connect the body and jack, an operating rod carried by the body and having a projecting tongue to connect with the piston rod, and a shaft carried by the body having a projecting foot for operating the stem, the body, operating rod and

shaft being substantially parallel with each other.

14. In combination, a jack having a socket, an operating pump with a reciprocating piston rod, and a release valve with an exposed operating stem, and an operator including an elongate body having a handle at its inner end, a laterally projecting finger at the outer end of the body engageable in the socket to connect the body and jack, an operating rod carried by the body and having a laterally projecting tongue to connect with the piston rod, and a shaft carried by the body having a laterally projecting foot for operating the stem.

15. In combination, a jack having a socket, an operating pump with a reciprocating piston rod, and a release valve with an exposed operating stem, and an operator including an elongate body having a handle at its inner end, a finger at the outer end of the body engageable in the socket to connect the body and jack, an operating rod carried by the body and having a projecting tongue to connect with the piston rod, an operating lever pivotally connected with the body and with the operating rod and a shaft carried by the body having a projecting foot for operating the stem.

16. In combination, a jack having a socket, an operating pump with a reciprocating piston rod, and a release valve with an exposed operating stem, and an operator including an elongate body having a handle at its inner end, a finger at the outer end of the body engageable in the socket to connect the body and jack, an operating rod carried by the body and having a projecting tongue to connect with the piston rod, operating means for the operating rod carried by the body and operable to reciprocate said operating rod and a shaft carried by the body having a projecting foot for operating the stem.

17. An actuator for a jack having two operating parts one a pressure generating part and the other a pressure release including, an elongate body, means at one end of the body releasably engageable with the jack to couple the actuator and jack, an elongate member carried by the body and movable relative to the body, means at the other end of the body engaging one end of said member and operable to work said member relative to the body, means at the other end of said member engageable with the pressure generating part to operate it, a second elongate member carried by the body and movable relative thereto, and means carried by said second member positioned to operatively engage the pressure release when the actuator is coupled to the jack.

18. A mechanism of the character described including, a base, a jack cylinder projecting vertically from the base, a jack piston operable in the cylinder, a liquid reservoir carried by the base, a pump carried by the base with a reciprocating element projecting laterally of the jack cylinder and having fluid connection with the cylinder and reservoir to pump liquid from the reservoir to the cylinder, pressure release means including a duct in connection with the cylinder and the reservoir and a valve controlling the duct and having an exposed operating stem, the base having an open socket angularly related to the pump, an elongate body having a lateral projection at one end engageable in the socket to releasably couple the body and base, an elongate operating member carried by the body and having a part releasably engageable with the reciprocating element of the pump, and a second elongate operating member carried by the body with a part op-

eratively engageable with the stem of the valve when the body is coupled to the base and the first mentioned member is engaged with the reciprocating part of the pump.

19. A mechanism of the character described including, a base, a jack cylinder projecting vertically from the base, a jack piston operable in the cylinder, a liquid reservoir carried by the base and surrounding the cylinder, a pump carried by the base with a reciprocating element projecting laterally of the jack cylinder and reservoir and having fluid connection with the cylinder and reservoir to pump liquid from the reservoir to the cylinder, pressure release means including a duct in connection with the cylinder and the reservoir and a valve laterally offset from the pump and controlling the duct and having an exposed upwardly projecting operating stem, the base having an upwardly opening socket angularly related to the pump, an elongate body having a lateral projection at one end engageable in

the socket to releasably couple the body and base, an elongate operating member carried by the body and having a laterally projecting part releasably engageable with the reciprocating element of the 5 pump means carried by the body operable to actuate said member, and a second elongate operating member carried by the body with a laterally projecting part operatively engageable with the stem of the valve when the body is coupled to the base and the first mentioned member is engaged with the reciprocating part of the 10 pump.
